GUSTAV A. AICHER, DECEASED, LATE OF SAN FRANCISCO, CALIFORNIA, BY OLGA J. AICHER, EXECUTRIX, OF SAN FRANCISCO, CALIFORNIA

SHOOK LABELING MACHINE

Application filed March 18, 1930. Serial No. 436,787.

This invention relates to improvements in shook labeling machines wherein shooks, or the like, fed onto a moving carrier, are moved past mechanism for applying adherent upon desired portions of the surface of each shook and past mechanism for feeding labels singly from a supply of labels and applying said labels upon the adherent portions of the shooks.

10 The primary object of the invention is to provide an improved machine for applying labels upon shooks and the like.

Another object is to provide an improved machine, for labeling shooks, having improved label feeding and applying means.

A further object is to provide an improved label feeding and applying mechanism which is efficient in operation and which is automatically rendered inoperative in the absence 20 of a shook to receive a label.

Another object is to provide an improved label feeding mechanism which is simple and positive in its action and which is operative for labels and shooks of various size.

25 A further object is to provide an improved mechanism for applying labels which is adapted to prevent marring or distortion of the labels and by which the labels may be applied smoothly upon a desired portion of 39 the surface of a shook.

A further object is to provide an improved labeling mechanism wherein the operating elements are positively and accurately timed with respect to each other, and which is efficient and durable in operation.

Another object is to provide improved labeling mechanism provided with improved means for applying adhesive upon the desired limited or restricted portions of shooks 43 to receive labels of various size, positioned in a desired manner upon the shook.

A further object is to provide an improved labeling machine having in combination an improved carrier of simple and efficient construction and operation and which carrier may be easily adjusted to accommodate shooks of various size.

A further object is to provide an improved machine of the character described which 50 may be operated continuously for long pe-

riods of time and which requires a minimum of attention when in service.

A still further object is to provide an improved labeling machine embodying improved structures and arrangements of parts 55 simplifying the construction, adjustment, and operation of the machine, and increasing the operative efficiency.

These and other objects are accomplished by means of the improved device disclosed in the drawings forming a part of the present application wherein like characters of reference are used to designate similar parts throughout the specification and drawings, and in which—

Fig. 7 is a broken detail showing the feeding member moved to carry a label into engagement with the gripping means;

Fig. 8 is a broken sectional detail of the 80 feeding and applying mechanism taken upon the line 8—8 of Fig. 5 in the direction indicated;

Fig. 9 is a broken detail of the valve actuating mechanism for the feeding member in a position corresponding to Fig. 8;

Fig. 10 is a broken detail of the gripper actuating mechanism positioned to correspond to Fig. 8;

Fig. 11 is a view similar to Fig. 8 with the feeding member moved to feeding position;

Figs. 12 and 13 are details similar to Figs. 9 and 10 with the parts positioned to correspond to Fig. 11;

Fig. 14 is a view similar to Figs. 8 and 11, with the several parts moved to show the manner in which a label is released onto the applying roller;

Figs. 15 and 16, are broken details of the 100

gripper and valve actuating means respectively in positions corresponding to Fig. 14;

Fig. 17 is a view similar to Figs. 8, 11, and 14, showing the applying roller in position to release a label onto a shook;

Figs. 18 and 19 are views similar to Figs. 15 and 16 with the parts moved to positions corresponding to Fig. 17;

Fig. 20 is a plan view of the frame and shook carrier;

Fig. 21 is a transverse sectional detail of the carrier, drawn upon a larger scale;

Fig. 22 is a broken sectional detail of the feeding and gripping mechanism;

Fig. 23 is a broken sectional detail showing the manner in which a label is engaged by gripping means;

Figs. 24, 25 and 26, are broken sectional details of the feeding valve operating mechanism in various positions;

Fig. 27 is an enlarged sectional detail of the feeding member, and its actuating mechanism; and

Fig. 28 is a broken sectional detail of the shook feeding detent.

Referring to the drawings, the numeral 1 is used to designate in general a supporting frame-work. A shook carrier designated in general by the numeral 2 is mounted upon the upper portion of the frame-work 1, said carrier comprising a pair of parallel endless conveyor chains mounted over sprockets 3 carried by shafts 4 and 6 extending transversely across the frame adjacent the ends thereof. The sprockets 3 upon the driving end of the carrier are feathered onto the shaft 4 by means of a suitable key-way 7, while the sprockets 3 at the opposite end of the carrier are both rotatably and slidably movable upon the shaft 6. Each chain 2 is provided with a plurality of shook engaging lugs 8 arranged at regularly spaced intervals, the lugs of the chains being arranged in matching relation.

The carrier 2 is actuated by means of a suitable source of power, such as an electric motor 9 mounted upon a bracket 11 upon the lower portion of the frame 1. The motor 9 is provided with a pulley 12 to receive a belt 13 connected over a pulley 14 secured upon a shaft 16 mounted transversely across the frame 1 adjacent the driving end of the carrier. The shaft 16 is provided with a pinion 17 meshing with a gear 18 mounted upon a shaft 19 extending transversely across the frame 1. The gear 18 has a pinion 21 secured in connection therewith and meshing with a gear 22 secured upon the shaft 4, the gears and pinions being designed to obtain a proper reduction of speed between the motor and the carrier driving shaft 4. The gears 18 and 22 are mounted upon the outer side of the framework 1 and are preferably covered by suitable guards 23 and 24.

A suitable shook holder designated in general by the numeral 26 is mounted upon the

frame 1 above one end of the carrier 2. The holder 26 is arranged to receive a supply of shooks, or box ends 27 stacked therein and arranged to be delivered from the bottom of the holder. The stack of shooks is supported upon a pair of rails 28 with the lowermost shook 27 just clearing the upper surfaces of the carrier chains 2, as best shown in Fig. 21 of the drawings.

Detents are mounted adjacent the bottom of the holder 26 upon the forward side thereof, each detent comprising a roller 29 mounted upon a slidable member 31 actuated by a spring 32 to normally hold the roller in a position opposite the forward edges of the two lowermost shooks. The axis of each roller 29 is opposite the edge of the shook next to the bottom, and the lower edge of the roller normally extends slightly below the upper edge of the lowermost shook. The lugs 8 extend upwardly from the chains 2 sufficiently to engage the rearward edge of the lowermost shook. As the carrier is operated, the pairs of lugs 8 are moved against the rearward edge of the then lowermost shook and force said shook forwardly from under the stack of shooks, the rollers 29 being forced upwardly against the pressure of the springs 32 sufficiently to permit the movement of the lowermost shook thereunder while still operating to hold the second shook against forward movement. As the lowermost shook is moved from under the stack, the remaining shooks drop down onto the rails 28 in position for the then lowermost shook to be engaged and moved forwardly by the next approaching pair of lugs 8. The supply of shooks in the holder 26 is maintained automatically or by hand as desired.

The sprockets 3, over which the carrier 2 operates, are adjustable longitudinally of the shafts 4 and 6 by means of adjusting members 33 mounted upon shafts 34 and 34' extending transversely across the frame 1 in spaced parallel relation to the shafts 4 and 6. The shafts 34 and 34' are each provided with right and left hand threads upon opposite ends thereof, said threads engaging the adjusting member whereby a rotation of the shafts 34 and 34' operate to move the adjusting members 33 simultaneously in opposite directions to move said members apart or together as desired. The members 33 are provided with arms 36 slidably engaging the shafts 4 and 6 and embracing the sprockets 3 whereby the movement of said members 33 operates to adjust the spacing of the sprockets 3 upon each shaft 4 and 6 to accommodate various widths of shooks 27. A chain 35 is connected over sprockets 35' secured upon the shafts 34 and 34' whereby the shafts may be rotated simultaneously by means of a suitable crank 35" mounted upon one of said shafts.

Carrier guides 37 are connected at their

ends to the adjusting member 33 at opposite ends of the frame 1. The guides 37 are angular in form with upwardly extending flanges formed upon their outer edges to 5 form guides for the sides of the shooks, the guides being adjusted with the members 33 to accommodate various widths of shooks. The guides 37 are provided with tracks 38 engaged by the rollers 2' of the carrier chains 10 to support the links 2" of said chains clear from the guides 37, as best shown in Fig. 21 of the drawings, whereby the weight of the chains and the shooks 27 carried thereon, together with downward pressure applied upon 15 the shooks, is carried by the rollers, thereby preventing wear upon the links, and reducing the frictional resistance to movement of the carrier. The guides 37 with their tracks 38 maintain the upper course of the carrier 20 in a true horizontal plane along the entire length thereof.

A brush 39 is mounted transversely across the top of the frame 1 immediately forward from the shook holder 26, the bristles of said 25 brush being arranged to sweep the surface of the shooks 27 as said shooks are moved forwardly from the holder. The brush is partially enclosed by a housing 40 and is driven by means of a belt 41 connected over pulleys 30 42 and 43 mounted upon the outer ends of the brush shaft and the shaft 16 respectively.

A roller 44 is mounted transversely across the top of the frame 1 in spaced parallel relation to the brush 39. The roller is provided 35 with a pad 46 of desired size and shape, secured upon the surface of the roller 44 and arranged to form a rolling contact with the surface of each shook moved thereunder by the carrier 2.

40 A suitable adhesive material is applied by the pad 46 onto the surface of each successive shook, said adhesive material being supplied from a trough 47 extending transversely across the frame 1. A roller 48 is rotatably 45 mounted within the trough and arranged to dip into the adhesive material contained therein. A roller 49 rotatably mounted in proximate relation to the roller 48 serves to displace surplus adhesive material picked up 50 by the roller 48. A roller 51 rotatably mounted in proximate contacting relation to the roller 48 and the surface of the pad 46 operates to transfer adhesive material from said roller 48 onto the pad 46.

55 The pad 46 is cemented or otherwise secured to the roller 44 whereby the pad may be removed and a pad of different size substituted when desired, the size of the pad being designed to conform to the size of the 60 label to be applied whereby adhesive will be applied by said pad onto the shooks 27 to cover only that portion of the shooks to which the label is to be applied.

A label holder, designated in general by 65 the numeral 52, is mounted above the carrier

2 to receive a supply of labels 53. The labels 53 are supported edgewise within the holder and are inclined only slightly from a vertical position, said labels being pressed against a retaining member 54 by a movable member 70 55. The labels are supported upon slats forming the bottom of the holder, and the lower edge of the retaining member 54 is spaced above the ends of the slats and above 75 the lower edges of the labels.

A label feeding member designated in general by the numeral 56 is rigidly secured upon a hollow shaft 57 mounted transversely across the machine immediately in back of the retaining member 54. The feeding member 56 80 is preferably yoke shaped and provided with a pair of spaced parallel arm portions 56' having suction passages 58 therein and also having suction openings 59 formed in the ends thereof. The passages 58 communicate 85 with the interior of the hollow shaft 57. The shaft 57 is mounted upon the upper ends of a pair of arms 61 pivoted by means of bearing portions 62 upon opposite sides of the machine at points alined with the lower edge 90 of the retaining member 54. One of the pivots 62 is provided with a lateral extension 63 engaged by a cam 64 secured upon a shaft 65 extending transversely across the frame 1, said extension being held in engagement with 95 said cam by means of a spring 66. The cam 64 is provided with a portion 67 arranged to move the extension 63 against the tension of the spring 66, thereby imparting an oscillating pivotal movement to the arms 61 and to 100 the feeding member 56.

The hollow shaft 57 is provided with a flexible connection 68 connected thereto and communicating with the hollow interior of the shaft. The connection 68 is connected to 105 a suction pipe 69 which in turn is connected to the suction side of a suitable pump 71, or other source of suction. The pump is actuated by means of a belt 72 driven by the motor 9. The suction pipe 69 is provided with a 110 suitable valve 73 operable to open and close the connection to the shaft 57 and feeding member 56, said valve being normally closed and being provided with a stem 74 arranged to be engaged by a cam 76 mounted upon the 115 shaft 65 for moving said valve to open position during a portion of each revolution of the shaft 65, as hereinafter more fully explained.

The shaft 65 is provided with a plurality 120 of drums 77 secured in spaced relation upon said shaft. A gripper shaft 78 is rotatably mounted through the drums 77 in spaced relation to the shaft 65. A gripper arm 79 is secured upon the shaft 78 within each drum, 125 said arms 79 being movable from an inoperative position within the drums to operative positions extending outwardly through openings 81 formed in the peripheries of the drums with the ends of said arms moved to 130

press against the outer surfaces of the drums adjacent said openings.

The shaft 78 extends through a disc 82 secured upon the shaft 65 adjacent one end thereof. A trip 83 is mounted upon the end of the shaft 78 adjacent the outer side of the disc 82, and a lever 84 is secured upon the shaft 78 adjacent the inner side of said disc 82. A spring 86 is mounted upon a guide rod 87 pivotally connected to the lever 84 and slidably and pivotally engaging a guide 88 secured to the disc 82, the spring being arranged to be compressed to impart a quick throw to the lever 84 and shaft 78 to either extreme position when the lever 84 passes the mid-point of its movement in either direction.

The trip 83 is provided with an outwardly disposed flange 83' having outwardly inclined portions formed at its ends. Pins 89 and 90 are rigidly secured upon a plate 91 secured to the frame 1 of the machine. The pins 89 and 90 are positioned in such manner that as the gripper shaft 78 is revolved around the shaft 65 with the drums 77, the flange 83' will engage the pins alternately. As the trip 83 is moved toward the pin 89, as indicated in Fig. 10, the flange 83' is moved against the pin. The further movement of the disc 82 with the shaft 65 and shaft 78 causes the trip 83 to rotate said shaft 78 relative to the drums 77 and disc 82 until the flange of said trip is swung to the inside of the pin 89. As the lever 84 passes the line between the axis of the shaft 78 and the guide 88, the spring 86 imparts a quick throw to the shaft 78, thereby carrying the flange 83' inwardly to clear the pin 89 and at the same time rotating the shaft 78 sufficiently to move the gripper arms 79 from their inoperative positions as shown in Fig. 8 to an operative position as shown in Fig. 11.

While the trip 83 occupies its inwardly turned position as shown in Figs. 13 and 18, the rotation of the shaft 65 causes the trip to be moved into contact with the pin 90 which is so positioned that as the end of the shaft 78 is carried past the pin 90, the trip will engage said pin 90 and the flange 83' will be turned to the outside, as shown in Fig. 15. As the lever 84 is moved past its center of movement, the spring 86 is compressed to impart a quick throw carrying the lever and shaft 78 to its opposite extreme position with the gripping arms 79 again moved to inoperative position within the drums 77. The pins 89 and 90 are so positioned relative to the axis of the shaft 65 that the flange 83' is moved to pass upon the inside of the pin 89 and upon the outside of the pin 90, and said pins are so spaced from each other as to move the gripping arms 79 to operative and inoperative positions through substantially 180° of rotation of the shaft 65.

65 A label applying roller 91 is mounted

transversely across the frame 1 parallel to the shaft 65 and in proximate relation to the surfaces of the drums 77, the roller 91 being arranged to form rolling contact with the upper surface of shooks 27 moved therewith by the carrier 2. The roller 91 is hollow and is provided with a suction connection 92 opening axially therewith, said roller also having openings 93 formed in the surface of the roller to communicate with the hollow interior of the roller.

The suction connection 92 is connected to the suction pump 71, preferably by connecting said connection 92 into the suction pipe 69 at a point between the valve 73 and the pump. The connection 92 is provided with a check valve 92' normally closing said connection and being operable by suction to open said connection when the valve 73 is closed or when the suction openings 59 of the feeding member 56 are closed by a label when the valve 73 is open. The connection 92 is also provided with a suction relief valve 94 having a valve member 95 normally seated to close a port 96 opening outwardly to the atmosphere. The valve member 95 is provided with a stem 97 arranged to be engaged by a cam 98 mounted upon the shaft 65 adjacent the cam 76 to open said port and relieve the suction within the hollow roller 92 and thereby release a label onto a passing shuck 27, as hereinafter more fully explained.

The drums 77 and the roller 91 are made of the same diameter, and the roller 44 including the pad 46 thereon is also made of the same diameter, said diameter being such that the circumference of said drums and rollers will equal the space between the lugs 8 along the carrier chains 2 whereby a complete revolution of the drums and rollers will bring the same points thereof into corresponding position relative to each shuck 27 as said shucks are moved successively therewith by the carrier.

The rollers 91 and 44 and the shaft 65 carrying the drums 77 are actuated in timed relation to the movement of the carrier 2 by means of a driving chain 101 driven by a sprocket 102 mounted upon one side of the machine. The chain 101 is mounted over a sprocket 103 adjustably secured upon the shaft 65 and over sprockets 104 and 106 secured upon the rollers 44 and 48 respectively. The chain extends over a chain guide roller 107 mounted upon an outwardly disposed extension 108 of the applying roller 91, and an idler sprocket 109 is mounted upon a slidably adjustable support 111 for adjusting the tension of the chain 101. The sprocket 102 is driven by the carrier drive shaft 4, said sprocket preferably being rotatably mounted upon the outwardly disposed extension of the shaft 34. The sprocket 102 is secured in connection with a gear 112 meshing with a similar gear 113 secured upon said shaft 4.

The shaft 65 is provided with a gear 114 meshing with a gear 116 secured upon the extension 108 of the applying roller 91 whereby rotation of the shaft 65 operates to drive the roller 91 in an opposite direction at the same speed. The meshing gears 114 and 116 effectually maintain the proper timing of the shaft 65 and roller 91 relative to each other.

The roller 48 is provided with a gear 117 meshing with gears 118 and 119 secured upon the rollers 49 and 51 respectively whereby said rollers are positively driven by said roller 48 to apply adhesive to the pad 46 of the roller 44.

A pair of delivery rollers 121 are mounted across the frame 1 upon the end adjacent the label feeding and applying means. The rollers 121 are provided with sprockets 122 engaged by the driving chain 101 whereby the rollers are both rotated in the same direction. The rollers 121 are preferably surfaced with rubber and are arranged to exert a resilient pressure onto the upper surfaces of shooks moved thereunder from the feeding and applying means whereby the labels are pressed firmly and smoothly onto the surface of the shooks as said shooks are delivered over the end of the carrier 2. The rollers 121 are adjusted by suitable adjusting members 123 to exert the desired degree of pressure upon the surfaces of the shooks.

A chute 124 is mounted adjacent the end of the frame 1 immediately below the delivery end of the carrier 2. Guide rails 126 are mounted to guide shooks from the carrier into inclined position as indicated in dotted lines in Fig. 2 of the drawings. A delivering member 127 is slideable within the chute 124 adjacent the end of the carrier 2 for moving the shooks forwardly along the chute as each successive shook is delivered thereto. The member 127 is actuated by means of a link 128 pivotally connected at one end to said member and at the opposite end to a lever 129 pivotally mounted upon the frame 1. A bell crank 131 pivotally mounted upon the frame 1 is connected to the lever 129 by a link 134 said bell crank also being provided with a roller 132 engaging a cam 133 mounted upon the shaft 4. The link 134 connects the lever 129 and bell crank 131 in such manner that a relatively short lift of the cam 133 will produce a relatively long movement of the member 127 to advance each successive shook from its delivery position upon the rails 126 into engagement with spring detents 136 mounted upon the sides of the chute as indicated in dotted lines in Fig. 2 of the drawings. The shooks within the chute 124 are moved forwardly as each successive shook is moved into the chute. The labelled shooks are removed from the chute 124 automatically or by hand as desired.

In operation, a supply of labels 53 is placed in the holder 52 and a supply of shooks 27, or

the like, is placed in the holder 26. The machine is then set in motion by the motor 9. As the carrier 2 is moved, a pair of lugs 8 engage the lowermost shook 27 in the holder 26 and move the same forwardly past the detents 29 and from under the stack of shooks, the next higher shook being retained by the detents 29 and the lower edge of the front wall of the holder.

As the shook 27 is moved forwardly, the brush 39 operates to sweep the upper surface free from dust or other loose foreign material. The shook is then moved forwardly under the roller 44 with its pad 46 the surface of which pad is coated with adhesive material applied thereto by the rollers 48, 49, and 51, operating as above described. The pad 46 is of substantially the same size and shape as the label to be applied and is so positioned upon the roller 44 that rotation of the roller as the shook 27 is moved thereunder will cause the pad to engage the desired portion of the shook and apply the adhesive thereon. The shook 27 is then moved forwardly toward the label applying roller and at the same time, the next pair of lugs 8 engage and move the next succeeding shook forwardly toward the brush 39 and roller 44.

As the first, and each successive shook 27, is moved forwardly past the brush 39, the shook engages a trip lever 137 pivotally mounted below the upper course of the carrier 2. The shook 27 is held down by a roller 138, thereby causing the trip 137 to be depressed to actuate a lever 139 against the normal tension of a spring 141, the lever 139 being mounted upon the shaft 142 upon which the trip lever 137 is secured. The lever 139 in turn actuates a link 143 connected to a bell crank 144 mounted adjacent the cam 76 secured upon the shaft 65. A wedge member 147 is pivotally mounted upon the crank 144 and is arranged to be moved by said crank to an operative position between the cam 76 and the stem 74 of the valve 73.

The operation of the trip 137 and wedge member 147 is illustrated in Figures 24, 25, and 26 of the drawings. Thus, when the trip lever 137 is in its normal raised position, the wedge member 147 is elevated to a position such that the thin lower end of the wedge is interposed between the cam 76 and the stem 74, as shown in Fig. 24. While in this position, the rotation of the cam 76 through its operative phase, as shown in Fig. 25, does not displace the wedge member sufficiently to engage the valve stem 74 and the valve 73 therefore remains in its normal closed position. When the trip lever 137 is depressed by a shook 27, the wedge member is moved downwardly to interpose its thick section between the cam 76 and the stem 74, whereby movement of the cam through its

operative phase, as shown in Fig. 26, causes said wedge member to be moved against the stem 74 and thereby open said valve while the high portion of the cam passes the wedge member. The shaft 142 is provided with a lever 148 whereby the trip 137 may be operated manually independently of a shook if desired.

As the shook 27 actuates the trip lever 137 and opens the valve 73, as above described, the cam 64 carried by the shaft 65 is moved to cause the extension 63 to be moved to the position shown in Figs. 9 and 27 of the drawings, thereby swinging the arms 61 upon their pivots 62 and moving the label feeding member 56 to the position shown in full lines in Figs. 9 and 27 of the drawings. This movement of the feeding member 56 causes the ends of the arm portions thereof to engage the label 53 immediately back of the retaining member 54 upon the portion immediately below the lower edge of said retaining member, the suction openings 59 being moved immediately against said label.

When the valve 73 is open, suction from the pump 71 operate through the suction pipe 69 and flexible connection 68 to draw and hold the adjacent label against the ends of the arm portions of the feeding member. As the shaft 65 is further rotated, the extension 63 is moved back from the high point of the cam 64 to its normal position by the spring 66, thereby returning the feeding member to the position shown in dotted lines in Fig. 27 and in full lines in Figs. 11, 14, 17, and 22, whereby the edge of the label held thereon by suction is moved against the surfaces of the drums 77 as shown in Figs. 7, 11, and 22.

While the edge of the label 53 is held against the drums 77, the rotation of the shaft 65 and drums 77 causes the trip 83 to engage the pin 89 and to swing said trip from the relative position shown in Fig. 10 to the position shown in Fig. 13 and thereby rotate the shaft 78 and move the gripper arms 79 from inoperative position as shown in Fig. 8 to operative gripping position as shown in Figs. 11 and 22. The ends of the gripper arms 79 move to grip the edge of the label against the surface of the drum. A gripping pin 151 is preferably slidably movable through an opening 152 formed in the periphery of each drum 77 and actuated by a spring 153 within the drum to normally extend slightly outwardly from the drum in a position to be engaged by the gripping arms when moved to gripping position. The outwardly extending ends of the pins 151 are knurled to cooperate with the gripping arms to insure an efficient gripping of the labels. As the rotation of the shaft 65 and drums 77 is continued, the label is drawn away from the feeding member 56 and pulled from the holder 52, said label being

rolled onto the drums as said drums are rotated.

As the edge of the label 53 is moved between the proximate surfaces of the drums 77 and the applying roller 91, the trip 83 is moved to engage the pin 90 whereby the trip is caused to turn the shaft 78 and move the gripping arms 79 to release the label, as shown in Fig. 14. The suction openings 93 of the roller 91 are arranged to be moved into contact with the label carried by the drums 77 at the moment the label is released by the gripper arms 79, the suction from the pump 71, operating past the check valve 92', causing the edge of the label to be held onto the roller 91 and to be carried over said roller as shown in various positions in Figs. 8, 11, and 17. Guards 149 are mounted concentrically with the roller 91 and in spaced relation to the upper portion thereof to direct the label away from the drums 77 and around the roller 91, should the label become disengaged from the roller 91 by an inadvertent breaking of the suction in the roller.

The roller 91 reaches the position shown in Fig. 17 as the shook 27 is moved thereunder so that the label 53 is rolled onto the portion of the shook which has been rendered adhesive by contact with the pad 46. At the instant the forward edge of the label contacts with the shook, the relief valve 96, is opened to relieve the suction within the roller 91, the cam 98 being timed to engage the stem 97 and actuate the valve member 95 and thereby open the port 96 in timed relation to the rotation of the roller 91. The label being thus released from the roller 91 is laid smoothly onto the shook and is carried forwardly by the shook to the rollers 121. The rollers 121 operate to press the label firmly onto the shook.

The labelled shook is then carried forwardly over the end of the carrier 2 and is received upon the rails 126 as indicated in dotted lines in Fig. 2. The member 127 is then moved as above described to force the shook forwardly along the chute 124, as indicated in dotted lines in Fig. 2.

The label feeding and applying mechanism is actuated in timed relation to the movement of the carrier so that a label is fed and applied upon each successive shook. In event a shook is not fed to the carrier, the trip 137 is not actuated and the valve 73 will not be opened. In this event, no suction will be applied through the feeding member 56 to engage a label from the supply contained in the holder 52 and hence no label will be fed onto the drums 77 and applying roller 91.

The check valve 90 operates to normally close the connection to the roller 91. In starting the machine, when no label is being carried by the roller 91, the openings 93 would permit an intake of air such that no appreciable suction would be present in the feeding member 56 to engage and feed a label.

The check valve 92' operates to close the connection to the roller 91 until the suction through the pipe 69 exceeds the spring resistance of the check valve. Thus, when the 5 valve 73 is opened and the arms of the feeding member 56 are moved to pick up a label, the openings 59 are closed by said label and the resulting suction will operate to unseat the check valve and obtain a suction in the 10 roller 91. When the relief valve 94 is opened, the check valve 92' again operates to close the connection and insure suction to the feeding member to engage and feed the next label.

The area of each shook to which the adhesive is applied is varied according to the size of the label by correspondingly varying the size of the pad, as above explained. To vary the position of the label upon the shook, the carrier 2 is moved to position the lugs 8 in a 20 desired relation to the timing of the roller 44 and the label feeding and applying mechanism. This is accomplished in the structure herein disclosed by loosening the slide mounting 111 carrying the idler sprocket 109 and moving said sprocket to permit the chain 101 to be removed from the several sprockets driven thereby. The carrier 2 is then advanced or receded the desired amount without altering the timing of the roller 44 and said label feeding and applying means. The chain 101 is then replaced in operative engagement with the several sprockets. As this change in adjustment may cause the chain 101 to be moved out of mesh with the 30 sprocket 103 driving the shaft 65, said sprocket is provided with slots 154 engaged by securing members 155 whereby the sprocket may be adjusted, relative to the shaft 65, to mesh with the chain without altering 35 the timing of the shaft 65. As the label feeding and applying mechanism is timed with respect to the forward edge of the labels fed, the carrier 2 may be adjusted so that the edge of each label will be placed at a uniform 40 distance from the foremost edge of each shook, thus insuring an efficient operation with various sizes of shooks and labels. The shaft 16 is provided with a hand wheel 157 whereby the machine may be operated manually 45 for making adjustments.

The suction feeding arms operate to efficiently separate the labels singly from the supply, and the gripping means operates to withdraw said labels from the supply and 50 to transfer the same onto the applying roller without subjecting the labels to excessive strain and without marring or disfiguring the labels in any way.

The carrier 2 together with the guides 37 55 may be quickly and efficiently adjusted to accommodate shooks of various widths. Adjusting means 156 are also provided in connection with the rollers 44, 91, and shaft 65, whereby the same may be adjusted to accommodate shooks of various thickness.

While only the preferred embodiment of the invention has been disclosed and described in the drawings and specification of the present application, numerous modifications may be made in the general construction and arrangement of the machine, as well as in the specific details of construction of the several parts of the machine. It is therefore desired to include all modifications which may fall within the scope of the 70 appended claims. 75

Having thus described the invention, what is claimed as new and desired to be secured by Letters Patent is:—

1. A shook labeling machine comprising a carrier; means for feeding shooks onto the carrier; means for rendering desired portions of the shooks adherent; suction operated label feeding means operating in timed relation to the movement of shooks therewith by the carrier; means for moving labels from the feeding means onto the adherent portions of the shooks; and means preventing the feeding of a label in the absence of a shook upon the carrier to receive the same. 80

2. A shook labeling machine comprising a carrier; means for feeding shooks onto the carrier; means for rendering desired portions of the shooks adherent; suction operated label feeding means operating in timed relation to the movement of shooks therewith by the carrier; label gripping means mounted adjacent the feeding means to engage labels delivered by the feeding means; and means for carrying the labels from the gripping means onto the adherent portions of the shooks. 85

3. A shook labeling machine comprising a carrier; means for feeding shooks onto the carrier; suction operated label feeding means operating in timed relation to the movement of shooks by the carrier; a roller mounted adjacent the feeding means and provided with gripping means engaging labels fed thereto by the feeding means; and means for carrying labels from the gripping means onto the shooks. 90

4. A shook labeling machine comprising a carrier; means for feeding shooks onto the carrier; suction operated label feeding means operating in timed relation to the movement of the shooks by the carrier; a gripper roller mounted adjacent the feeding means and provided with gripping means engaging labels fed thereto by the feeding means; and a suction roller mounted adjacent the gripper roller to carry labels from said gripper roller and to apply said labels upon the shooks. 95

5. A shook labeling machine comprising a carrier; means for feeding shooks onto the carrier; suction operated label feeding means operating in timed relation to the movement of the shooks by the carrier; a gripper roller mounted adjacent the feed-

ing means and provided with gripping means engaging labels fed thereto by the feeding means; a suction roller mounted adjacent the gripper roller to carry labels from said gripper roller and to apply said labels upon the shooks; and means preventing the feeding of a label in the absence of a shook upon the carrier to receive the same.

6. A shook labeling machine comprising a carrier; means for feeding shooks onto the carrier; means for rendering desired portions of the shooks adherent; a pair of pivotally mounted suction feeding arms movable to engage labels and move the same singly by suction from a supply of labels; and means to pick up labels from the arms and to apply the same upon the adherent portions of shooks moved therepast by the carrier.

7. A shook labeling machine comprising a carrier; means for feeding shooks onto the carrier; means for rendering desired portions of the shooks adherent; a pair of feeding arms mounted adjacent a supply of labels, said arms having a suction passage and suction opening and being movable to engage said supply; means for producing suction within the arms to hold labels in engagement with the arms to separate labels singly from the supply; gripping means to engage and move labels from the arms; and means to carry the labels from the gripping means onto the adherent portions of the shook.

8. A shook labeling machine comprising a carrier; means for feeding shooks onto the carrier; means for rendering desired portions of the shooks adherent; a pair of feeding arms mounted adjacent a supply of labels, said arms having a suction passage and suction opening and being movable to engage said supply; means for producing suction within the arms to hold labels in engagement with the arm to separate labels singly from the supply; gripping means to engage and move labels from the arms; means to carry the labels from the gripping means onto the adherent portions of the shooks; and means automatically closing the suction from the arms to prevent the feeding of a label thereby in the absence of a shook upon the carrier to receive the same.

9. A shook labeling machine comprising a carrier; means for feeding shooks onto the carrier; means for rendering desired portions of the shooks adherent; a pair of feeding arms mounted adjacent a supply of labels, said arms each having a suction passage and a suction opening and being movable to engage said supply; means for producing suction within the arms to hold labels in engagement with the arms to separate labels singly from the supply; gripping means mounted adjacent the arms to engage and remove labels from the arms; and label applying means mounted adjacent the gripping

means, said applying means operating by suction to remove labels from the gripping means and to carry said labels onto the adherent portions of the shooks.

10. A shook labeling machine comprising a carrier; means for feeding shooks onto the carrier; means for rendering desired portions of the shooks adherent; a pair of feeding arms mounted adjacent a supply of labels, said arms each having a suction passage and a suction opening and being movable to engage said supply; means for producing suction within the arms to hold labels in engagement with the arms to separate labels singly from the supply; gripping means mounted adjacent the arms to engage and remove labels from the arms; label applying means mounted adjacent the gripping means, said applying means operating by suction to remove labels from the gripping means and to carry said labels onto the adherent portions of the shooks; and means for breaking the suction of the applying means in timed relation to the movement of shooks therepast to release the labels onto said shooks.

11. A shook labeling machine comprising a carrier; means for feeding shooks onto the carrier; means for rendering desired portions of the shooks adherent; a pair of feeding arms mounted adjacent a supply of labels, said arms each having a suction passage and a suction opening and being movable to engage said supply; means for producing suction within the arms to hold labels in engagement with the arms to separate labels singly from the supply; gripping means mounted adjacent the arms to engage and remove labels from the arms; label applying means mounted adjacent the gripping means, said applying means operating by suction to remove labels from the gripping means and to carry said labels onto the adherent portions of the shooks; and means for breaking the suction of the applying means in timed relation to the movement of shooks therepast to release the labels onto said shooks; and means automatically closing the suction from the arms to prevent the feeding of a label thereby in the absence of a shook upon the carrier to receive the same.

12. A shook labeling machine comprising a carrier; means for feeding shooks onto the carrier at regular intervals; a roller extending across the carrier and provided with a pad engaging the upper surface of each successive shook; means for supplying an adherent onto the pad to be applied thereby onto the shooks; a holder mounted adjacent the carrier to contain a supply of labels; feeding arms mounted adjacent the holder and movable to engage the outermost label of the supply, said arms operating by suction to separate the labels singly from the supply; gripping drums mounted adjacent

- the feeding arms and provided with gripping means actuated in timed relation to the movement of the arms and of the carrier to engage and move successive labels from the arms and from the supply; a label applying roller mounted adjacent the gripping drums and rotated in timed relation thereto, said roller operating by suction to engage labels carried by the gripping rollers and to carry said labels onto shooks moved successively therepast by the carrier, the gripping means being automatically actuated to release the labels as said labels are engaged by the applying roller.
13. A shook labeling machine comprising a carrier; means for feeding shooks onto the carrier at regular intervals; a roller extending across the carrier and provided with a pad engaging the upper surface of each successive shook; means for supplying an adherent onto the pad to be applied thereby onto the shook; a holder mounted adjacent the carrier to contain a supply of labels; feeding arms mounted adjacent the holder and movable to engage the outermost label of the supply, said arms operating by suction to separate the labels singly from the supply; gripping drums mounted adjacent the feeding arms and provided with gripping means actuated in timed relation to the movement of the arms and of the carrier to engage and move successive labels from the arms and from the supply; a label applying roller mounted adjacent the gripping drums and rotated in timed relation thereto, said roller operating by suction to engage labels carried by the gripping rollers and to carry said labels onto shooks moved successively therepast by the carrier, the gripping means being automatically actuated to release the labels as said labels are engaged by the applying roller.
14. A shook labeling machine comprising a carrier; means for feeding shooks onto the carrier at regular intervals; a roller extending across the carrier and provided with a pad engaging the upper surface of each successive shook; means for supplying an adherent onto the pad to be applied thereby onto the shooks; a holder mounted adjacent the carrier to contain a supply of labels; feeding arms mounted adjacent the holder and movable to engage the outermost label of the supply, said arms operating by suction to separate the labels singly from the supply; gripping drums mounted adjacent the feeding arms and provided with gripping means actuated in timed relation to the movement of the arms and of the carrier to engage and move successive labels from the arms and from the supply; a label applying roller mounted adjacent the gripping drums and
- rotated in timed relation thereto, said roller operating by suction to engage labels carried by the gripping rollers and to carry said labels onto shooks moved successively therepast by the carrier, the gripping means being automatically actuated to release the labels as said labels are engaged by the applying roller; valve means automatically actuated to break the suction of the applying roller and release each label as said label is moved to engage a shook; and valve means for automatically breaking the suction of the feeding arms to prevent the feeding of a label in the absence of a shook upon the carrier to receive the same.
15. In a shook labeling machine, label feeding means comprising a hollow feeding member connected to a source of suction and having a suction opening movable against a supply of labels to engage and separate labels singly from the supply; means mounted adjacent the feeding member to engage and move successive labels from the feeding member onto successive shooks moved therepast; and valve means automatically actuated by the movement of the shooks to open and close the suction connection to the feeding member in timed relation to the movement of said shooks.
16. In a shook labeling machine, label feeding means comprising a holder to receive a supply of labels supported edgewise in substantially vertical position; a hollow feeding member mounted adjacent the holder and connected to a source of suction and having a suction opening movable to engage the adjacent label near the lower edge thereof, and to separate said edge from the supply; and means mounted adjacent the feeding member to engage said separated edge of each successive label and operating in timed relation to the movement of shooks carried therepast to move said labels onto the shooks.
17. In a shook labeling machine, label feeding means comprising a hollow feeding member having a suction opening movable against the outermost label of a supply of labels supported adjacent said member; a source of suction; and a suction connection connecting the member with the source of suction, said means including a valve, automatically actuated by the movement of shooks to be labeled, to open said suction connection as each shook is moved toward the feeding member whereby the feeding member operates by suction to move and feed a single label for each shook.
18. In a shook labeling machine, label feeding means comprising a hollow feeding member having a suction opening movable against the outermost label of a supply of labels supported adjacent said member; a source of suction; a suction connection connecting the member with the source of suction, said means including a valve, automatically actuated

ated by the movement of shooks to be labeled, to open said suction connection as each shook is moved toward the feeding member whereby the feeding member operates by suction to move and feed a single label for each shook; and means to pick up each successive label from the feeding member and to apply said labels upon successive shooks.

19. In a shook labeling machine, label feeding means comprising a hollow feeding member having a suction opening movable against the outermost label of a supply of labels supported adjacent said member; a source of suction; a suction connection connecting the member with the source of suction, said means including a valve, automatically actuated by the movement of shooks to be labeled, to open said suction connection as each shook is moved toward the feeding member whereby the feeding member operates by suction to move and feed a single label for each shook; gripping means mounted adjacent the feeding member and operating in timed relation to said member to pick up each successive label from said feeding member; and means for transferring each successive label from the gripping means onto successive shooks.

20. In a shook labeling machine, label feeding means comprising a hollow feeding member having a suction opening movable against the outermost label of a supply of labels supported adjacent said member; a source of suction; a suction connection connecting the member with the source of suction, said means including a valve, automatically actuated by the movement of shooks to be labeled, to open said suction connection as each shook is moved toward the feeding member whereby the feeding member operates by suction to move and feed a single label for each shook; gripping means mounted adjacent the feeding member and operating in timed relation to said member to pick up each successive label from said feeding member; and a suction roller mounted adjacent the gripping member and operating in timed relation thereto to carry labels from said gripping means onto successive shooks.

21. In a shook labeling machine, label feeding means comprising a hollow feeding member having a suction opening movable against the outermost label of a supply of labels supported adjacent said member; a source of suction; a suction connection connecting the member with the source of suction, said means including a valve, automatically actuated by the movement of shooks to be labeled, to open said suction connection as each shook is moved toward the feeding member whereby the feeding member operates by suction to move and feed a single label for each shook; a shaft rotatably mounted adjacent the feeding member; drums secured upon the shaft; gripping elements mounted in connection

with the drums and automatically actuated to grip the edges of labels fed thereto by the feeding member and to move said labels onto the drums; and a label applying roller mounted in proximate parallel relation to the drums to carry the labels from said drums onto shooks.

22. In a shook labeling machine, label feeding means comprising a feeding member having a suction passage and a suction opening movable against the outermost label of a supply of labels supported adjacent said member; a source of suction; a suction connection connecting the member with the source of suction, said means including a valve, to open and close said suction in timed relation to the movement of shooks past the feeding member; gripping means mounted adjacent the feeding member and operating in timed relation to said member to pick up each successive label from said feeding member; a roller mounted adjacent the gripping member and having a suction chamber and suction openings movable to contact with labels carried by the gripping means to move labels by suction onto said roller and to carry said labels onto shooks moved therewith; means connecting the suction chamber with the source of suction, said means being provided with a suction relief valve; and means for automatically opening said valve to relieve the suction within the chamber and release the labels from the roller onto the shooks.

23. In a shook labeling machine, label feeding means comprising a feeding member having a suction passage and a suction opening movable against the outermost label of a supply of labels supported adjacent said member; a source of suction; a suction connection connecting the member with the source of suction, said means including a valve, to open and close said suction in timed relation to the movement of shooks past the feeding member; gripping means mounted adjacent the feeding member and operating in timed relation to said member to pick up each successive label from said feeding member; a roller mounted adjacent the gripping member and having a suction chamber and suction openings movable to contact with labels carried by the gripping means to move labels by suction onto said roller and to carry said labels onto shooks moved therewith; means connecting the suction chamber with the source of suction, said means being provided with a suction relief valve; means for automatically opening said valve to relieve the suction within the chamber and release the labels from the roller onto the shooks, said means also being provided with a check valve normally closed and movable to open position by suction when the suction passage of the feeding member is closed.

24. In a shook labeling machine, label

- feeding means comprising a member actuated in timed relation to the movement of successive shooks therpast and operating by suction to separate labels singly from a supply of labels supported adjacent thereto; label applying means operating by suction to engage and move a label into each shook; and means for moving the labels from the feeding means to the applying means.
25. In a shook labeling machine, label feeding means comprising a feeding member actuated in timed relation to the movement of successive shooks therpast to engage and move labels singly from a supply of labels supported adjacent thereto; label applying means mounted adjacent the path of shooks to deliver labels onto the surfaces of successive shooks; and means for moving the labels from the feeding means to the applying means.
- 10 20 means, said means being provided with grippers automatically actuated in timed relation to the feeding and delivering means to grip labels fed thereto by the feeding member and to release said labels to the applying means.
25. 26. In a shook labeling machine, label feeding means comprising a feeding member actuated in timed relation to the movement of successive shooks therpast and operating by suction to engage and move labels singly from a supply of labels supported adjacent thereto; label applying means mounted adjacent the path of the shooks and operating by suction to engage and deliver labels onto the shooks; and means mounted intermediate the feeding member and the applying means and provided with gripping arms actuated in timed relation to said feeding member and applying means to grip labels fed thereto by the feeding member and to release said labels to the applying means.
- 30 35 40 45 50 55 60 65 70 75 80 85 90 95 100 105 110 115 120 125 130
27. In a shook labeling machine, label feeding means comprising a feeding member actuated in timed relation to the movement of successive shooks therpast and operating by suction to engage and move labels singly from a supply of labels supported adjacent thereto; label applying means mounted adjacent the path of the shooks and operating by suction to engage and deliver labels onto the shooks; means mounted intermediate the feeding member and the applying means and provided with gripping arms actuated in timed relation to said feeding member and applying means to grip labels fed thereto by the feeding member and to release said labels to the applying means; and means for automatically connecting and disconnecting the feeding means with a source of suction in timed relation to the movement of shooks therpast.
28. In a shook labeling machine, a shook carrier comprising a pair of shafts; sprockets mounted upon the shafts; a pair of endless conveyor chains mounted over the sprockets; a pair of adjusting shafts mounted adjacent the sprocket shafts and having right and left handed threads formed thereon at opposite ends thereof; adjusting members threaded onto the adjusting shafts and provided with arms engaging the sprocket shafts and sprockets for shifting the sprockets longitudinally along said sprocket shafts; means for rotating one of the adjusting shafts to move the adjusting members thereon simultaneously in opposite directions to vary the space between the sprockets and chains; means for connecting said adjusting shaft to the opposite adjusting shaft to rotate the same and move the adjusting members thereon a corresponding amount; and tracks connected at opposite ends to the adjusting members to opposite ends of the carrier to support the chains between the sprockets and to form guides for shooks fed onto the carrier.
29. In a shook labeling machine, a label feeding member provided with a suction passage and suction openings movable to engage a label to be fed to the machine; a label applying roller having a suction chamber and having openings arranged to engage labels by suction; a suction connection connecting the feeding member with a source of suction; a connection connecting the applying roller to the suction connection; and a check valve mounted in the applying roller connection and normally closing the same, said valve being movable by suction to open said connection when the feeding member openings are closed by a label.
30. In a shook labeling machine, a label feeding member provided with a suction passage and suction openings movable to engage a label to be fed to the machine; a label applying roller having a suction chamber and having openings arranged to engage labels by suction; a suction connection connecting the feeding member with a source of suction; a connection connecting the applying roller to the suction connection; a check valve mounted in the applying roller connection and normally closing the same, said valve being movable by suction to open said connection when the feeding member openings are closed by a label; a relief valve mounted in the roller connection between the check valve and said roller; and means for automatically opening said relief valve in timed relation to the operation of the applying roller.
- In witness whereof, I have hereunto set my signature.
